(57) **CLAIM**

The ornamental design for a set of chess pieces, as shown and described.

DESCRIPTION

FIG. 1 is a front perspective view of a set of chess pieces, showing my new design therefor;

FIG. 2 is a front perspective view of a first piece from the set of chess pieces shown in FIG. 1, showing my new design therefor;

FIG. 3 is a frontal view of the design shown in FIG. 2, the left side, the right side, the rear, the top, and the bottom views being identical thereto;

FIG. 4 is a front perspective view of a second piece from the set of chess pieces shown in FIG. 1, showing my new design therefor;

FIG. 5 is a frontal view of the design shown in FIG. 4, the left side, the right side, and the rear views being identical thereto;

FIG. 6 is a top view of the design shown in FIG. 4;

FIG. 7 is a bottom view of the design shown in FIG. 4;

FIG. 8 is a front perspective view of a third piece from the set of chess pieces shown in FIG. 1, showing my new design therefor;

FIG. 9 is a frontal view of the design shown in FIG. 8, the left side, the right side, and the rear views being identical thereto;

FIG. 10 is a top view of the design shown in FIG. 8; and FIG. 11 is a bottom view of the design shown in FIG. 8;

FIG. 12 is a front perspective view of a fourth piece from the set of chess pieces shown in FIG. 1, showing my new design therefor;

FIG. 13 is a frontal view of the design shown in FIG. 12, the left side, the right side, and the rear views being identical thereto;

FIG. 14 is a top view of the design shown in FIG. 12;

FIG. 15 is a bottom view of the design shown in FIG. 12;

FIG. 16 is a front perspective view of a fifth piece from the set of chess pieces shown in FIG. 1, showing my new design therefor;

FIG. 17 is a frontal view of the design shown in FIG. 16, the left side, the right side, and the rear views being identical thereto;

FIG. 18 is a top view of the design shown in FIG. 16, the bottom view being identical thereto;

FIG. 19 is a front perspective view of a sixth piece from the set of chess pieces shown in FIG. 1, showing my new design therefor;

FIG. 20 is a front view of the design shown in FIG. 19, the rear view being identical thereto;

FIG. 21 is a side view of the design shown in FIG. 19, showing the left side, the right side being identical thereto;

FIG. 22 is a top view of the design shown in FIG. 19; and, FIG. 23 is a bottom view of the design shown in FIG. 19.
